UNITED STATES PATENT OFFICE

CHARLES LEDIN, OF STAMFORD, CONNECTICUT, ASSIGNOR TO THE YALE & TOWNE MANUFACTURING COMPANY, OF STAMFORD, CONNECTICUT

PADLOCK

Application filed April 27, 1928. Serial No. 273,372.

This invention relates to padlocks of the type used for railroad switch work. The object of the invention is to provide a simple but very durable mechanism, which will be capable of securely locking the shackle of the padlock and which, at the same time, will be able to withstand attempts at picking the locking mechanism.

In the drawing, Figure 1 represents my padlock with the shackle locked. Figure 2 shows the padlock with the shackle fully opened. Figure 3 is a front and side view of my shackle heel locking tumbler. Figure 4 is a front and side view of my shackle nose locking tumbler. Figure 5 is a view of my shackle ejecting tumbler.

Referring to the drawings, reference numeral 1 refers to the usual type of casing used for this type of padlock, and 2 indicates the shackle, which is provided with a nose locking portion 3 and a heel locking portion 4. A tumbler 5 is spring pressed by the spring 6 in a direction to lock the nose of the padlock by means of the hook portion 7. A second tumbler 8 is spring pressed by a spring 9 in a direction whereby its tail portion 10 will act to lock the shackle by cooperation with the shackle heel locking portion 4.

As will be noted, the heel locking tumbler 8 is equipped with a pin 11 which is adapted when the tumblers are in locking position to lie within a slot 12 in the nose locking tumbler 5. It is quite obvious from this construction that in order to release the shackle, it is necessary to first remove tumbler 8 from locking position so as to withdraw the pin 11 from the slot 12. Otherwise, it is impossible to remove tumbler 5 from its locking position. This construction will require a certain sequence of operation of the tumblers, and is quite effective in preventing the picking of the padlock.

A further feature of my padlock is the shackle ejecting tumbler 13, which is pivoted on the pin 14 which supports the tumbler 8. This shackle ejecting tumbler is loosely held within the padlock casing and normally rests by means of gravity against the pin 15 upon which is mounted the heel locking tumbler 8. The padlock shackle is equipped

with a shackle extension 16 and the tumbler 13 is adapted when the tumblers are released to be actuated by a key to cooperate with the portion 16 to eject the shackle when the same has been released by its tumblers. The key employed in this type of padlock may be of any desired construction, but herein I use a key having a hollow stem, which is adapted to fit over the key post 17.

This key is shown in section at 18 and in actual operation it will move so as to first actuate the tumbler 8, to release the shackle heel and remove the pin 11 from the slot 12. It will then cooperate with the tumbler 5 so as to release the nose of the shackle. Further operation will cause it to actuate the tumbler 13 so as to force the portion 13' of said tumbler against the shackle extension 16 so as to eject the shackle.

I claim:

1. In a padlock, a casing, a shackle equipped with toe and heel locking portions, a tumbler for locking said shackle at its toe portion, a second tumbler for locking said shackle at its heel portion, a pin carried by said second tumbler for locking said first tumbler until said second tumbler is released by a proper key, and a shackle ejecting tumbler in said casing adapted to be actuated by the key to eject the shackle when it has been released by its tumblers.

2. In a padlock, a casing, a shackle pivoted therein, and equipped with toe and heel locking portions, a pair of tumblers independently pivoted for independently locking said toe and heel, a pin on one of said tumblers cooperating with a slot on the other of said tumblers to lock the same until said first tumbler is released, an extension arm at the heel of the shackle, and a shackle ejecting tumbler loosely held on a tumbler pivot and cooperable with said shackle extension when actuated by a key to eject the shackle when the same is released by the tumblers.

Signed at Stamford, in the county of Fairfield and State of Connecticut, this 25th day of April, A. D. 1928.

CHARLES LEDIN.
